MESNE ASSIGNMENTS, TO AMERICAN BEMBERG CORPORATION, A CORPORATION
OF DELAWARE

**EXCHANGEABLE FILTER, MORE PARTICULARLY FOR ARTIFICIAL-SILK-SPINNING
MACHINES**

Application filed November 27, 1925, Serial No. 71,663, and in Germany January 15, 1925.

In artificial silk spinning machines so-called filter cartridges are inserted in the fine spinning nozzles immediately before the inlet for the spinning solution in order to 5 remove the last impurities from the spinning solutions. Of course such filter cartridges have to be replaced from time to time by fresh ones. Owing to the changing however a certain amount of still unfiltered 10 solution can very easily pass over on to the clean side and the penetration of air is also not precluded. To make good these two involves loss of time and material.

In order to remove these disadvantages the 15 arrangement has been suggested of inserting in the pipe in a stationary position a plurality of filters in parallel so as to make it possible to work without interrupting the flow of liquid. Owing to the employment 20 of numerous cocks however which had to be operated in a definite sequence when changing over, the danger arose of unfiltered solution passing over, of air entering and of the flow of liquid being interrupted. These 25 dangers were further increased by the necessity of changing the filter body. In the case of the filter according to the present invention all this is obviated because the changing over is effected positively and the 30 filters during the cleaning remain in the liquid-filled casing.

The filter according to the present invention is characterized by the feature that two or more individual filters are arranged on a 35 movable under-frame in such a way that by properly displacing the frame the filters can be brought singly into the cleaning position, the working position and the position of rest. In the constructional form of the subject- 40 matter of the invention described later an arrangement resembling a revolving head is provided wherein the individual filters are located upon a rotatable base which can be moved in a circle round a stationary central 45 member. The base and the central member are provided with passages in such a way that in a particular position one filter is in the working position while the other filter or filters are either completely disconnected 50 or so connected with the central member

that the cleaning of the filters is effected by the backward flowing or purified liquid.

The details of the invention are given in the following specification:

In the accompanying drawing 55
Fig. 1 shows in part diagrammatically in section the general arrangement according to the invention;

Fig. 2 is in part a section through the stationary central member on the line A—B in 60 Fig. 1;

Fig. 3 is partly a plan with the filter in position on the left hand side and the filter removed on the right hand side and partly a section on the line C—D in Fig. 1 through 65 the stationary central member;

Fig. 4 is a view similar to Fig. 1, but with the filters in a different position relative to the stationary central member;

Fig. 5 is a plan of Fig. 4. 70

The liquid to be filtered passes through an inlet pipe union *b* of a branch piece *a* into a stationary cock plug *d*, see Fig. 1. From the bore of the plug the liquid to be filtered passes into a passage *g* of a rotatable cock casing *n* and then flows into a bell *e* to a filter cartridge *f*. From the interior of the filter cartridge *f* the filtered solution passes back through a passage *h* into the cock casing *n* and flows on through another bore into the cock plug *d* which in turn is connected with a second pipe union *b'* of the branch piece *a*, whence the purified liquid is transmitted to the place where it is to be used. 75

Fig. 1 shows the rotatable casing which is 80 of symmetrical construction on both sides and which also carries two filter cartridges, with bells. If the filter cartridge *f* has become choked a cleaned second filter *f'* can be put in place of the first by simply rotating the cock casing *n* and consequently the filtering can be carried on almost without interruption. 85

The cleaning of the filter *f* is not effected 90 by taking it out but by rinsing it back with fresh filtered solution from the interior of the cartridge outwards whereby the dirt is tapped off out of the bells *e*, *e'* from the outer side of the cartridges through the cocks *Z*, this being done in the position ac- 95 100

cording to Fig. 4 on the right-hand side in which the filter f' to be cleaned is only connected with the cock plug d through the fresh liquid passage h' . Figs. 4 and 5 accordingly show one filter cartridge f in operation, both passages of the casing and also of the plug being for this filter open for filtering, and the second filter f' in the cleaning position, the passage g' for the unpurified liquid having no corresponding bore and hence being closed so that the rearwardly flowing purified liquid flows away, with the dirt that has been removed, through the right-hand cock Z .

15 Figs. 1, 2 and 3 also show one cartridge filter in operation, but the other completely shut off by the plug d . In this position the filter that is shut off can in exceptional cases be opened.

20 Thus there serves for the controlling of the filters a five-way plug, the ducts in which correspond to symmetrically arranged double passages in the rotatable casing n .

25 After the filter has been cleaned, it is advisable to completely fill the bell surrounding it with liquid in order that the cartridge within the bell may be completely immersed. If air is allowed to remain in the bell, air bubbles will enter the outlet pipe with the 30 liquid conveyed to the spinning nozzle and will cause interruptions and imperfections in the thread. The pipes i and i' , which are connected with the interior of the bells e and e' respectively, and which may be provided with suitable valves (not shown), are 35 connected to a suitable suction means (not shown) and when the suction is applied the bell may be completely filled with the liquid which is allowed to flow into it through the 40 inlet conduit g or g' .

Figs. 3 and 5 show the exchangeable filter in plan, the bores of the cock plug also being shown. The passage for the impure liquid opens on to two transverse bores (Fig. 45 3), while the passage of the purified liquid only opens on to three transverse bores in the plug (Fig. 2). Each of the passages is connected with a pressure indicator r and r' respectively. o and p are adjusting rings 50 with screw threads on the plug for making a fluid-tight closure between plug and casing. The outer bells e and e' and also the covers k for closing the filter cylinders are pressed on tight by means of conical screws l and 55 w and screw-threaded spindles m .

What I claim is:

1. An exchangeable filter for machines for the spinning of artificial silk comprising a plurality of individual filters, a rotatable 60 member on which said filters are carried, a fixed base on which said rotatable member is mounted, said fixed base having a part in the form of a cock plug with a double branched inlet and a triply branched outlet, 65 said rotatable member being provided with

inlets and outlets arranged diametrically opposite to one another and capable of being connected to the inlets and outlets of said fixed member, said individual filters having individual outlets arranged to be opened for the discharge of backwardly flowing liquid during the cleaning of the filter. 70

2. In a filter structure the combination with a valve plug member and a pair of filter chambers adapted to be rotated thereabout, of a double branched conduit and a triple branched conduit in said valve plug, each having terminals so positioned that one of the filter chambers will be in operative position, in one position of the filter chambers relative to the valve plug member, while the other filter chamber is in inoperative position, and so that in another position of the filter chambers relative to the valve plug the filtered fluid which has passed through one of the chambers will be permitted to pass in a reverse direction through the other chamber and thereby cleanse the same. 80

3. In a filter structure the combination with a pair of filter chambers, each of which has a conduit terminating in a common plane and a second conduit terminating in another common plane, of a valve plug for controlling the fluid passing through said conduits, said valve plug having separate inlet and outlet conduits, one of which has two branches terminating in one of said common planes and the other of which has three branches terminating in the other of said common planes. 90

4. In a filter structure the combination with a filter chamber having two conduits terminating at different heights, and a second filter chamber having two conduits terminating at points diametrically opposite said first mentioned terminals, of a valve plug adapted to control the fluid in said conduits by rotation relative to the terminals thereof, said valve plug having separate inlet and outlet conduits, one of which has a triple branch with two sections terminating at points 180° from each other in the plane of the diametrically opposed terminals of conduits in the filter chambers and with a third section terminating in the same plane and at 90° to the line connecting the terminals of the other sections, and the other of which has a double branch, each section of which terminates at 90° from the other and in the plane of the remaining diametrically opposed terminals of conduits in the filter chambers. 100

5. In a filter structure the combination with a plurality of filter chambers, each of which has a conduit terminating in a common plane and a second conduit terminating in another common plane, of a valve plug for controlling the fluid passing through said conduits, said valve plug having separate inlet and outlet conduits, one of which has a plurality of branches terminating in one of said common planes and the other of which has a 110

plurality of branches terminating in the other of said common planes.

6. In a filter structure the combination with a plurality of filter chambers, each having a conduit terminating in a common plane and a second conduit terminating in another common plane, of a fixed valve plug for controlling the fluid passing through said conduits, said valve plug having separate inlet and outlet conduits, one of which conduits has a plurality of branches terminating in one of said common planes and the other of which conduits has a plurality of branches terminating in the other of said common planes.

15 In testimony whereof I have signed my name to this specification.

WALDEMAR ZUR LÖWEN.
